UNITED STATES PATENT OFFICE.

JACOB H. FRIEDENWALD, OF BALTIMORE, MARYLAND.

SHOCK-ABSORBER.

942,896.

Specification of Letters Patent. Patented Dec. 14, 1909.

Application filed June 19, 1909. Serial No. 503,083.

To all whom it may concern:

Be it known that I, JACOB H. FRIEDENWALD, a citizen of the United States, residing at Baltimore, Maryland, have invented 5 certain new and useful Improvements in Shock-Absorbers, of which the following is a specification.

My invention relates to improvements in shock absorbers designed more especially 10 for use in connection with motor vehicles, and consists in the novel construction and arrangement and combination of parts hereinafter described, and particularly set forth in the appended claims.

15 The invention is illustrated in the accompanying drawings in which:—Figure 1 is a side elevation, and Fig. 2 a detailed view.

Referring by reference characters to this drawing, the shock absorber is shown as 20 comprising a pair of upper links 1, which are pivotally connected to each other and to a suitable part of the body of the car, indicated at 2, by a pivot pin 3. These links have their lower ends pivotally connected by 25 pivots 4 to a pair of cross arms 5 which are pivotally connected together at 6 and have their lower ends pivotally connected by pivots 7 with the upper ends of links 8, which are duplicates of the links 1 but reversed in 30 position. The links 8 have their lower ends pivotally connected by a pivot pin 9 which is also in connection with a clip 10, which is secured in any suitable manner to the axle of the car indicated at 10^a. The two sets of 35 pivots and connecting cross arms thus described constitute a doubled toggle joint construction. The pivots 4 and 7 are provided with projections which are designed to be connected by elastic means. I prefer to 40 make the elastic connections in the form shown in the drawings, in which a rod 10^a is provided having one end secured to a cross piece 11 and guided at the other end by a similar cross piece 11^a through an opening 45 in which it projects, the projecting portion being connected to the extended part of the corresponding pin 4. The cross piece or block 11^a carries side bars or rods 12, which project through openings in the cross piece 50 or block 11 and are connected by a suitable bracket 13 with the extension of the other pivot pin 4. It will thus be seen that as the

pivot pins tend to separate or move away from each other, the two cross pieces 11 and 11^a will be moved toward each other and 55 this movement is resisted by a compression spring 14, encircling the rod 10 between the two cross pieces. The links 1 and 8 are all preferably curved outwardly as shown to form as it were hooks 15, which are connected by spring devices 16 similar to those which extend between the pivots 4—4 and 7—7, these vertically disposed spring devices acting in opposition to the transverse spring device. 60

It will be understood of course that this device is used in connection with and supplemental to the ordinary vehicle springs and I have not deemed it necessary to show such springs in the present drawing. 70

As the ordinary springs yield under the influence of inequalities in the road and the body lowers the transverse springs are placed under a rapidly increasing tension, thus tending to assist the main springs and 75 relieve them of undue strain and prevent breaking, while when on rebound the main springs lift the body above the neutral point the side vertical springs are placed under a similar tension. 80

Having thus described my invention, what I claim is:—

1. In a shock absorber, a pair of crossed arms pivotally connected together, links connecting the opposite ends of the arms with a vehicle axle and vehicle body respectively, and horizontally and vertically disposed springs connected to act at right angles to each other on said crossed arms, substantially as described. 85

2. In a shock absorber device, a pair of crossed arms pivotally connected together, links pivotally connecting the upper ends with a vehicle body, links connecting the lower ends of the crossed arms with the axle, horizontally disposed elastic devices extending across the toggle frames formed by said arms and links, and vertically disposed elastic devices extending between the extremities of the upper and lower links. 95

3. In a shock absorber, a pair of crossed arms pivotally connected together, links pivotally connecting the upper ends with a vehicle body, links for connecting the lower

ends to the crossed arms with a vehicle axle, |
said links having extended hooked ends,
horizontally disposed elastic devices extend-
ing across the toggle frames formed by said
5 arms and links, and vertically disposed elas-
tic devices extending between said hooked
ends of the upper and lower links.

In testimony whereof, I affix my signature
in presence of two witnesses.

JACOB H. FRIEDENWALD.
